CLAIM

The ornamental design for headphones, as shown and described.

DESCRIPTION

FIG. 1 is a right-side elevational view of the headphones;
FIG. 2 is a front elevational view thereof;
FIG. 3 is a left-side elevational view thereof;
FIG. 4 is a rear elevational view thereof;
FIG. 5 is a top plan view thereof; and,
FIG. 6 is a bottom plan view thereof.

The broken lines in the drawings are provided to show features and boundaries that form no part of the claimed design.

1 Claim, 6 Drawing Sheets
